(57) **CLAIM**

The ornamental design for a siding panel, as shown and described.

DESCRIPTION

FIG. 1 is a top front isometric view of a siding panel showing my new design.

FIG. 2 is a front view of the siding panel of FIG. 1.

FIG. 3 is a rear view of the siding panel of FIG. 1.

FIG. 4 is a right side view of the siding panel of FIG. 1.

FIG. 5 is a left side view of the siding panel of FIG. 1.

FIG. 6 is a top view of the siding panel of FIG. 1; and,

FIG. 7 is a bottom view of the siding panel of FIG. 1.

The broken lines in the drawings depict portions of the siding panel that form no part of the claimed design.

The present invention relates in general to exterior cladding for buildings and, in particular, to a siding panel for a building.
